Attorney

UNITED STATES PATENT OFFICE.

AUGUST P. CLOT, OF WEEHAWKEN HEIGHTS, NEW JERSEY.

MULTIBLADED KNIFE.

1,240,946.

Specification of Letters Patent. Patented Sept. 25, 1917.

Application filed November 24, 1916. Serial No. 133,179.

To all whom it may concern:

Be it known that I, AUGUST P. CLOT, a citizen of the United States, residing at Weehawken Heights, in the county of Hudson and State of New Jersey, have invented certain new and useful Improvements in Multibladed Knives, of which the following is a specification.

The present invention relates to cutlery and has particular reference to new and useful improvements in multi-bladed thread cutting implements, the device having for its primary object the provision of a multi-bladed cutter in which the blades are capable each of independent relative adjustment so as to cut along different lines.

Another object of my invention is to provide a device of the character described which is simple in construction, compact, strong and durable and effective in operation.

A further object of my invention is to provide a device of the character described which is applicable for use in connection with the making of embroidered goods, it being the common practice with the present machines to leave two short lengths of thread extending between the various designs, it being necessary to cut these threads after the design is completed. My invention contemplates the provision of a multi-bladed knife capable for use in this connection, leaving only one length of thread if so required whereby the threads mentioned being longer may be quickly and accurately severed.

Other objects of my invention not hereinbefore set forth will appear from the following detailed description and the claims, taken with an inspection of the accompanying drawings, in which:

Figure 1 is a top plan view of a multi-bladed knife embodying the improvements of my invention;

Fig. 2 is an end elevational view of the same;

Fig. 3 is an enlarged detailed perspective of an extension blade; and

Fig. 4 is a similar view of one of the intermediate blades.

Referring more particularly to the drawings, wherein similar characters of reference designate like and corresponding parts throughout the various views, 10 designates the main body plate of my invention, the same having a tapering shank 11 extending

therefrom, said shank being riveted as at 12 to said base plate. A handle 13 is carried by the shank 11.

The blade holder includes a channel-iron 14 having the outer marginal edges thereof formed with lateral oppositely arranged flanges 15, the free margins of said flanges being in spaced relation to permit passage therebetween of a retaining screw 16, said screw having a head 17 engageable beneath the flanges and a wing nut 18 engageable with the shank of the blade to be retained thereby.

In view of the fact that all of the blades with the exception of the extension blades are identical in construction, I shall describe but one of the same. Referring specifically to Fig. 4 I have illustrated one of the intermediate blades, the same having a base body portion 20 offset as at 21 to engage one side of the channel 14, said body, beyond the offset portion being extended as at 22 and bifurcated as at 23 to be engaged by one of the screws 16. This is best shown in Fig. 1. The blade is designated 24 and is formed along one margin of the base 20, said blade 24 having a cutting edge inclined toward the front end of the base portion 20. The front end of said base portion is rounded as at 25 and serves as a guide as well as a carrier or body for the blade. The marginal edge of the body 20 engages the blade and serves as a guide, said margin being brought into alignment with one of the various graduations 26 formed on one of the flanges 15.

I provide extension blades relatively oppositely arranged at the free ends of the channel 14, said blades being provided to increase the scope of the cutting action of the device. One of the extension blades, in this instance the left hand blade, is shown in detail in Fig. 3. Referring specifically to Fig. 3, I provide a cutting element embodying a base supporting portion 28 having a blade 29 formed along one free margin thereof, said blade having a slanting cutting edge. The body 28 is formed with a vertical laterally extending channel member 30, the top portion of which is formed with a slot 31, said slot opening at one free end of the channel member.

The cutting elements, when assembled are mounted preferably as shown in Fig. 1, all of the blades being adjustably arranged on the channel 14, and all of said blades being

relatively adjustable. I desire to call attention to the arrangement of the extension blades, said blades being relatively oppositely disposed, that is, the blades thereof being arranged so as to more readily coöperate with the intermediate cutting elements. In many cases the extension blades do not need to be used and may be left out, at other times only those on the left or right depending on the pattern of the embroidery.

In Fig. 1 an illustration of one use of the device is shown by the dotted line design above the cutting elements, portions of the design proper being designated 33, assuming different shapes, the working thread being designated 34 and extending before being cut between said figures or designs.

The blades in use, are adapted to pass between the figures 33 of the design and sever the threads 34. Of course, I do not limit myself to the use as specified but the device is primarily designed for this purpose. I desire to direct attention to the arrangement of the cutting edges whereby danger of cutting the cloth or other fabric is eliminated, only a smooth surface being presented to the cloth when the device is moved thereover.

From the above description taken in connection with the accompanying drawings, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Having thus fully described my invention, what I claim as new and desire to secure by Letters Patent, is:

1. In a knife, the combination of a plate having a channel member thereon provided with inwardly directed flanges, said flanges being arranged in spaced relation to form a slot, a plurality of cutting elements having bifurcated ends, said cutting elements being offset to engage said channel, and securing screws extending through the bifurcated portions of said cutting elements and between said flanges for the purpose specified.

2. In a knife of the class described, the combination of a base plate having a channel member thereon provided with spaced inwardly directed flanges to form a slot, and a plurality of cutting elements provided with offset portions to engage said channels, said offset portions being extended to bridge the flanges, and means engaging with the flanges and said extended portions to adjustably maintain said cutting elements on said base plate.

3. In a knife of the class described, the combination with a base plate having a channel member thereon provided with inwardly directed flanges in spaced relation to form a slot, and a plurality of intermediate cutting elements adjustably arranged on said channel-member, of end extension cutting elements comprising channel portions, base portions, said channel portions being provided with slots, means engaging with said flanges and said channels to adjustably maintain said extension cutting elements in position, and the base portions of said cutting elements having vertically arranged blades.

4. In a knife of the class described, the combination of a base plate having a channel-iron arranged thereon, said channel-iron being formed with a pair of spaced parallel inwardly directed flanges for providing a slot between them, a cutting element associated with said base plate having means to engage said channel, and means extending through said cutting elements and engageable with said flanges for adjustably maintaining said cutting element on said plate.

5. In a device of the class described, the combination of a base plate having a channel member thereon, a plurality of intermediate independently and relatively adjustable blades carried by said channel member, and a pair of extension blades carried by the free ends of said channel member, said extension blades being relatively adjustable and adjustable relative the intermediate blade.

In testimony whereof, I affix my signature hereto.

AUGUST P. CLOT.
